UNITED STATES PATENT OFFICE.

WALTER H. SMITH, OF NILES, OHIO, ASSIGNOR TO THE HARRIS AUTOMATIC PRESS COMPANY, OF NILES, OHIO, A CORPORATION OF OHIO.

MEANS FOR COUPLING FEEDERS OR THE LIKE TO PRINTING-PRESSES.

1,079,370.

Specification of Letters Patent.

Patented Nov. 25, 1913.

Application filed April 26, 1911. Serial No. 623,487.

To all whom it may concern:

Be it known that I, WALTER H. SMITH, of Niles, in the county of Trumbull and State of Ohio, have invented certain new and useful Improvements in Means for Coupling Feeders or the like to Printing-Presses; and I do hereby declare the following to be a full, clear, and exact description of the invention, such as will enable others skilled in the art to which it appertains to make and use the same.

The objects of this invention are to provide simple and highly efficient means for effecting a coupling between a printing press and coöperative mechanism, such as a feeder; to provide for properly timing the stopping or throwing out of action of such coöperating mechanism, either manually or automatically; to insure the restarting or throwing into action of the coöperating mechanism at the proper point to bring about the necessary coöperative action with the press; and also to guard against liability of breakage in the event of any mishap 25 with the coöperating mechanism when the same is in coöperative relation with the press.

The invention will be hereinafter fully set forth and particularly pointed out in the claims.

In the accompanying drawings, Figure 1 is a side elevation of a portion of a printing press, and a feeder. Fig. 2 is an enlarged side view, looking outwardly from one side 35 of the feeder frame, showing the prime mover coupled to the driving shaft of the feeder. Fig. 3 is a sectional view on lines 3—3 Fig. 2. Fig. 4 is a vertical sectional view showing the parts in the position they 40 occupy when the coupling is attempted at the wrong moment. Fig. 5 shows a slight modification.

Referring to the drawings, 1 designates the frame of a printing press, a portion only 45 of which frame is indicated in Fig. 1; 2 is the impression cylinder and 3 the plate-carrying cylinder, or it may be the transfer-cylinder of an off-set press.

4 is a clamping plate which is attached 50 to press frame 1 by set screws 5; such plate serving to clamp to the press frame a tie rod 6 forming part of frame 7 of coöperating mechanism which it is desired to hold fast to the press frame and yet permit 55 of ready detachment. In the present in-

stance this coöperating mechanism is a feeder which may be of any preferred construction, and which is conventionally indicated at 7^a Fig. 1 and is shown as having a stock conveyer in the form of a series 60 of rollers.

The prime mover for the feeder is shown in the form of a clutch disk 8 fast on a short shaft 9 whose bearing 9^a is bolted or otherwise secured to the press frame. This shaft 65 carries a beveled pinion 10 which is driven by a second beveled pinion 11 fast to the shaft of a gear 12 which is driven by gear 14 of the press gearing, which, in the present instance is shown as on the impression 70 cylinder shaft 15. The clutch disk 8 on its outer vertical face has a tooth 8^a. 16 designates a second clutch disk which has on its outer vertical face a tooth 16^a which is designed to engage tooth 8^a of disk 8. This 75 disk 16 is splined on a second shaft 17 in axial line with shaft 9, and this shaft 17 drives the feeder, its rotation being communicated to the latter by any suitable mechanism. The disk 16 is capable of moving longitudinally of shaft 17, and it has an extended hub upon which is a nut 18. The movement of disk 16 longitudinally of its shaft is effected through a rocking yoke 19 which carries two pins 20 which extend into 80 diametrically opposite holes of a friction collar 21 loose on the hub of said disk. A spring 22 attached to the feeder frame exerts a constant tension on the yoke, tending to pull it in the direction of the arrow, Fig. 90 2, to disengage disk 16 from the driving disk 8. Adjacent to friction ring 21, is a ball bearing 23, and next to the latter is a friction washer 24 between which and disk 16 is a coil spring 25, the tendency of which 95 is to force disk 16 into engagement with disk 8 when the yoke is moved toward the disks. If the teeth of the two disks should be in line when the disk 16 is moved toward disk 8 by yoke 19, resulting in their 100 engagement face on, as shown in Fig. 4, the spring 25 will be compressed, thus putting a spring tension, for the time being, on disk 16, which tension will cause such disk to move into proper position when the tooth of 105 disk 8 is moved out of engagement with the tooth of disk 16. This spring also allows the two disks to be forced apart in the event of an over-load on the feeder.

The yoke 19 is carried by a shaft 26 which 110

extends transversely of frame 7, and at that end opposite to that on which the yoke is carried this shaft carries a handle 27 and a toothed collar 28 with which latter a latch 29 is designed to engage when the yoke is moved in the direction to couple the driven shaft. To so move the yoke the handle 27 is raised, and is retained in its raised position by latch 29. (See Fig. 1.) The parts will 10 remain in the position thus described until latch 29 is tripped. This may be accomplished in various ways. I have shown this latch as having a handle 30 which may be manually moved to release shaft 26 and yoke 15 19 so that spring 22 may withdraw disk 16 from engagement with disk 8.

Inasmuch as the cessation of operation of the feeder should be properly timed, I provide means for preventing the disks from 20 being uncoupled at an inopportune point in the operation, even though latch 29 be disengaged from the collar of shaft 26. While the means for accomplishing this result may be widely varied, I have shown for this purpose 25 a latch 31 in the form of a lever fulcrumed on a stud 32, mounted on a bracket 33 extending laterally from the feeder frame 7. Upon the short arm of this latch lever is mounted a roller 34 which is held in engagement with a cam 36 fast to the driven or feeder shaft 17. This cam makes one 30 complete revolution for each cycle of operation of the feeder and press, and it has a peripheral projection for vibrating the latch lever 31 once in each cycle of operation. This latch normally occupies the position shown in Figs. 1 and 2, that is to say, the end of its long arm is normally raised and lies in line with a projection 35 of yoke 19, but 35 40 when the latch lever is vibrated the end of its long arm will be lowered out of the path of projection 35. If latch 29 is disengaged from collar 28 at the wrong time, latch 31 will prevent yoke 19 from moving sufficiently 45 to effect uncoupling until the latch lever is rocked by the cam. Hence this latch lever serves to retain the clutch disks in engagement, as against the action of spring 22, until the proper or predetermined point in 50 the cycle of operation has been reached. In other words, the manual tripping of latch 29 permits yoke 19 to move a slight distance in the direction of the arrow, Fig. 2, sufficient to prevent collar 28 being reengaged by latch 29, but the yoke will not move sufficiently to disengage the clutch disk 55 until the latch is vibrated, whereupon the yoke will complete its travel under the action of spring 22. The result just described 60 will also occur if the trip latch 29 is disengaged automatically instead of manually, but, under ordinary circumstances, when provision is made for automatically releasing the trip such action is timed so that the 65 yoke may immediately move disk 16 into

uncoupling position; but the described means makes it possible for the automatic tripping to be timed in different relation to the actual subsequent stopping of the feeder. The means for automatically disengaging the trip from the yoke shaft may also be widely varied.

In Fig. 1, I have shown a notched rod 40, connected to the throw-off shaft 42, of the press, designed to engage a pin 41 carried by the handle 30 of the latch 29. The throw-off shaft is preferably spring-impelled after the manner of the well known Harris press;—an instance of which is shown by Patent No. 966,256 issued to me August 2, 1910—and the release of this shaft results in the tripping of the impression, such release being effected automatically in the event of any interruption in the feed supply. The feeler lever for engaging the stock is conventionally indicated at 43 in Fig. 1. If stock is not in position at the proper time the feeler lever will effect the actuation of the trip mechanism, and a partial turning of shaft 42 will cause rod 40 to be moved to 90 disengage latch 29 from shaft 26, permitting the spring-impelled yoke to move in the direction of uncoupling, such movement, however, being prevented by the arresting lever 31 unless it occurs at the predetermined time when such lever is out of its normal position.

If desired, (see Fig. 5) the automatic release of the holding latch 29 may be effected other than by mechanical means. For instance, the handle 30 may be moved by energizing a magnet 44 in close proximity thereto, the closing of the circuit through the magnet being occasioned by the absence of stock in a manner well known in the art.

The arresting lever 31 is held in its normal position by a spring 45 attached to a pin 46 extending from bracket 33. I have shown a spring bumper 47 forming a cushion for the yoke when moved by spring 22.

The operation of the described mechanism is manifest from what has been hereinbefore stated, and repetition is unnecessary. It will be noted that by removing the screws 5 the feeder frame may be bodily removed from the press. The feeder can be returned and attached to the press, regardless of the position of clutch disk 16; that is to say, when the parts are in their normal position and again set in operation, the starting of the feeder will be properly timed without attention on the operator's part other than the partial turning of shaft 26. While this may be accomplished at any point, the actual rotation of the driven shaft 17 will occur only at a predetermined time; and likewise although the holding latch 29 may be disengaged from shaft 26, at any time, either manually or automatically, the 125 130

unclutching of the disks can occur only at a predetermined point. It will also be noted that if there is an over-load on the feeder the tooth or projection of the driving disk 8 may slip by the corresponding tooth or projection of the driven disk 16 without actuating the feeder shaft 17. The teeth of the two disks are of such formation that the feeder will not be turned backward if the press gearing be reversed, the angle of the teeth being such that upon reversing shaft 9 spring 25 will be compressed, allowing disk 16 to move longitudinally of its shaft.

I claim as my invention:

15 1. In combination with a printing press having a driving shaft, and a feeder having a driven shaft, coöperating clutch members carried by said shafts, one clutch member being movable longitudinally of its shaft,

20 means for moving such clutch member on its shaft to disengage it from the coöperative clutch member on the other shaft, means for normally arresting such movement, and means for actuating said arresting means

25 once in each cycle of operation to permit said clutch members to be disengaged.

2. In combination with a printing press having a driving shaft, and a feeder having a driven shaft, coöperating clutch members

30 carried by said shafts, one clutch member being movable longitudinally of its shaft, means for moving such clutch member on its shaft to disengage it from the coöperative clutch member on the other shaft, means for

35 normally holding said moving means to retain the members in coöperative relation, means for arresting said moving means if released by said holding means other than at a predetermined point in the cycle of operation,

40 and means for actuating said arresting means once in each cycle of operation to permit the clutch members to be disengaged.

3. The combination with a printing press and a shaft actuated thereby forming a driving

45 shaft, of a feeder, an operating shaft therefor forming a driven shaft, said shafts being in axial alinement, clutch members carried by said shafts and having interengaging projections, the clutch member of the

50 driven shaft being movable longitudinally thereof, means for so moving such member to disengage it from the member of the driving shaft, means for normally locking said moving means, means for arresting said

55 moving means when released by said locking means, and means for periodically actuating said arresting means to release said moving means at a predetermined point in the cycle of operation of the feeder.

60 4. The combination with a printing press and a feeder therefor, of a driving shaft, a clutch disk on said shaft, a driven shaft for operating said feeder, a second clutch disk

65 loose on said driven shaft for coöperating with the first mentioned disk, a yoke for

moving said disk on said driven shaft, a spring interposed between said disk and said yoke, means for normally holding said yoke, means for releasing said holding means, and periodically actuated means for permitting 70 said yoke to disengage the disks at a predetermined point in the cycle of operation of the feeder.

5. The combination with a printing press and a feeder therefor, of a driving shaft, a

75 driven shaft for operating said feeder, clutch members carried by said shafts, means for disengaging said clutch members, means for

normally locking said disengaging means, means for automatically releasing said locking

means in the event of any interruption in the feed supply to the press, arresting

means for preventing said disengaging

means from releasing said clutch members except at a predetermined point in the cycle

80 of operation of the feeder, and means for periodically actuating said arresting means.

6. The combination with a printing press having a driving shaft and a clutch mem-

ber therefor, of a feeder having a driven

90 shaft, a coöperating clutch member mov-

able longitudinally of said driven shaft,

a yoke, a spring interposed between said

yoke and said clutch member of the driven

shaft, a shaft carrying said yoke, a trip for

locking said shaft to cause said yoke to hold

95 said clutch members in coöperative relation,

means for releasing said trip, a lever de-

signed to arrest the movement of said yoke

if said trip is actuated other than that at a

predetermined point in the cycle of opera-

100 tion of the shaft,—and a constantly oper-

ating cam for actuating said lever at a pre-

determined point in such cycle of operation

105 to permit the yoke to disengage the clutch

members.

7. The combination with a printing press

having tripping mechanism and means for

actuating the same in the event of any inter-

ruption in the feed supply, of a feeder for

110 said press, a driving shaft, an operating

shaft for said feeder, actuated by said driv-

ing shaft, coöperating clutch members car-

ried by said shafts, said clutch members hav-

ing each a single projection, which projec-

115 tions are designed to normally engage with

each other, yielding means for normally

holding said clutch members in coöperative

relation to allow said projections to engage,

120 a trip for said holding means, and means ac-

tuated by the tripping of the press cylinders

for releasing said trip.

8. The combination with a printing press

having tripping mechanism, and means for

actuating the same in the event of any inter-

ruption in the feed supply, of a feeder for

125 said press, a driving shaft, an operating

shaft for said feeder, actuated by said driv-

ing shaft, coöperating clutch members car-

ried by said shafts, means for normally hold-

4
ing said clutch members in coöperative relation, a trip for said holding means, means actuated by the tripping of the press cylinders for releasing said trip, and means for preventing the unclutching of said members except at a predetermined point in the cycle of operation of the feeder.

In testimony whereof, I have signed this specification in the presence of two subscribing witnesses.

WALTER H. SMITH.
